WATCH DIAL OR SIMILAR ARTICLE

Karl Plepla, Pelham, N. Y., assignor to Superior Watch Corporation, New York, N. Y., a corporation of New York

Application April 13, 1951, Serial No. 14,813

Term of patent 14 years

(Cl. D42—10)

To all whom it may concern:

Be it known that I, Karl Plepla, a citizen of the United States, and a resident of Pelham, New York, have invented a new, original, and ornamental Design for a Watch Dial, or Similar Article, of which the following is a specification, reference being had to the accompanying drawing, forming a part hereof, in which

Figure 1 is a front elevational view of a watch dial, or similar article, showing my new design; and

Figure 2 is a section thereof on the line 2—2 of Figure 1.

The drawing is lined to indicate the colors blue, orange, green, yellow, gold and red.

I claim:

The ornamental design for a watch dial, or similar article, as shown and described.

KARL PLEPLA.
